UNITED STATES PATENT OFFICE.

WILLIAM ALBERT HICKMAN, OF WEST MYSTIC, CONNECTICUT.

BOAT.

Application filed January 10, 1923. Serial No. 611,887.

This invention pertains to improvements in boats. It is among the objects of the invention to improve the action of boats of the gliding or semi-gliding type.

5 In the drawings, which show preferred forms of my invention:

Figure 1 is a plan of a boat, being partly broken away and partly in section;

10 Fig. 2 is a section on the line 2-2 of Fig. 1, being partly in elevation;

Fig. 3 is a section on the line 2-2 of Fig. 1, showing a modified arrangement of rudder controls;

15 Fig. 4 is a stern elevation of the boat shown in Fig. 1;

Fig. 5 is a section on the line 5-5 of Fig. 4, being partly in elevation;

Fig. 6 is a section on the line 6-6 of Fig. 2;

20 Fig. 7 is a bottom plan view of the boat having the bow steering mechanism illustrated in Fig. 1;

Fig. 8 is a bottom plan view of the forward portion of the boat showing the rudder arrangement illustrated in Fig. 3 while steering to port; and

25 Figs. 9 and 10 are partial sections corresponding to Figs. 2 and 3 and showing the relation of the bow rudders when steering the boat to port.

Referring to the drawings and to the preferred embodiments of my invention selected for illustrative purposes, I have shown in Fig. 1 a boat having a hull 11 of the inverted V-bottom type, the bottom of which presents inverted V sections gradually broadening aft and preferably terminating in a substantially straight stern transom, as illustrated in Fig. 4, the construction being generally similar to that shown in my United States Patent No. 1,204,355, issued November 7, 1916. A portion of the boat amidships is broken away. Forward of amidships of the boat, I have shown rudder posts 12, 13 carrying vertically disposed rudders 14, 15, as best shown in Fig. 2, such rudder posts passing through the bottom of the boat at points substantially equidistant from the keel 16 and located at some distance from the chines 17, 18. The rudder posts 12, 13 are connected for joint operation by suitable mechanism typified by the bell cranks 19, 20 joined by connecting rod 21 and adapted to be swung in unison by a suitable flexible driving arrangement typified by the cable 22 passing over the sheaves

23 and 24 and wound around a drum 25 on the steering post of the boat.

The before-described rudder mechanism constitutes a preferred type of bow steering means. Bow steering means cooperating with a boat having a hull of the inverted V-bottom type is particularly efficient, because, as the rudders are turned to guide the boat in the desired direction, the rudder on the inside of the turn will always tend to pull down that side of the boat on the inside of the turn, while the rudder on that side of the boat adjacent the outside of the turn will bank the water against the bottom of the boat and tend to raise the adjacent side of the boat, thus effectively banking the boat for the turn, precluding the tripping of the side of the boat on the outside of the turn on the water, and banking that portion of the bottom of the boat adjacent the inside of the turn so that it presents an oblique surface to the water, which tends to oppose skidding without producing any tendency to trip. At the same time, when the boat is turning at great speed, an opportunity is afforded whereby the boat may swing or pivot on that portion of its keel adjacent the bow steering means, thus promoting quick turning without danger even when the boat is travelling at great speed.

In Fig. 3, I have shown a modification of bow steering means wherein the rudders 30, 31 are inclined inwardly, being shown substantially perpendicular to the adjacent bottoms of the boat, this inclination of the rudders increasing the banking action of the boat when turning arising from pulling down that side thereof at the inside of the turn and elevating the side of the boat adjacent the outside of the turn; the rudder on the inside of the turn will undercut the water and the opposite side of the boat will overcut or tend to plane on the water. Where the rudders are thus angled relative to one another, I may provide rudder controlling means typified by the rack 32 engaged by the pinion 33, which is connected to the steering wheel of the boat, the movement of the rack 32 being communicated to the rudders through connecting links 34, 35 providing suitable ball or other universal connections so that there will be no binding arising from the absence of alignment between the rudder pivots.

While the bow steering means is of advantage in inverted V-bottom boats of the plan-

ing or semi-planing type regardless of the type of propulsion used therewith, such steering means is particularly useful in connection with surface propulsion systems wherein the propeller hubs are at or slightly above the level of the water presented from beneath the adjacent bottom of the boat. I have shown in the present application surface propulsion means including a single propeller 40 having its hub 41 slightly above the bottom of the stern of the boat 42. To oppose lateral movement of the stern of the boat, tending to move the stern of the boat in the direction opposite to that in which the propeller blades move through the water, I have provided adjacent the propeller immersed plates 43 and 44, herein shown as extending forwardly and rearwardly of the propeller 40 and opposing lateral movement of the stern actuated by paddling operation of the propeller. Thus, if the propeller illustrated is turning in clockwise direction, as viewed in Fig. 4, the pressure on the inside of the plate 44 will be reduced while the pressure on the inside of the plate 43 will be increased, thereby causing pressure of the water on the outside of the plate 44 and on the inside of the plate 43 to overbalance the opposed pressure on the opposite sides of said plates and urging the stern of the boat to port, as viewed in Fig. 4, counteracting the paddling tendency of the wheel 40 to urge the stern to starboard. Where, as in the preferred form of my invention illustrated, the plates 43 and 44 are angled relative to one another so that their general planes will meet below the bottom of the boat, not only is lateral paddling action minimized by reason of the inclination cutting off the flow of water from below the plates, but steering action when turning at speed is facilitated because, when the stern of the boat starts to swing in turning at speed, the plates 43 and 44 will assist in banking the boat toward the inside of the curve. Thus if the boat, as viewed in Fig. 4, is turning to port, the plate 43 will undercut the water, dragging down the port side of the boat, while the plate 44 will overcut the water, tending to raise the starboard side of the boat, thus precluding tripping of the starboard side of the boat in the water and contributing to the anti-skidding action of that side of the inverted V-bottom of the boat toward the inside of the turn.

While I have shown and described preferred embodiments of my invention, it will be understood that I have done so for purposes of clarification and not for purposes of limitation. My invention is best defined in the following claims.

I claim:

1. A boat of the inverted V-bottom type having bow rudder means projecting through the bottom thereof and comprising

two rudders substantially equidistant from the keel and on opposite sides thereof.

2. A boat of the inverted V-bottom type having bow rudder means projecting through the bottom thereof and comprising two rudders substantially equidistant from the keel and on opposite sides thereof, said rudders connected for conjoint operation.

3. A boat of the inverted V-bottom type having bow rudder means projecting through the bottom thereof and comprising two rudders substantially equidistant from the keel and on opposite sides thereof; said rudders connected for conjoint operation and, when turning the boat, inclined relative to the direction of movement of the boat to undercut the water at that side of the boat adjacent the inside of the turn and to overcut the water at that side of the boat adjacent the outside of the turn.

4. A boat having a hull, a single surface propeller, and submerged means adjacent said propeller and subject to the lateral wash thereof opposing lateral movement of the stern of the boat due to the movement of the immersed portions of said propeller through the water, said submerged means angled to bank the boat when turning by depressing that side thereof toward the inside of the turn.

5. A boat having a hull, a single surface propeller, and submerged surfaces adjacent said propeller and subject to the lateral wash thereof opposing lateral movement of the stern of the boat due to the movement of the submerged surfaces of said propeller through the water, said immersed portions angled to bank the boat when turning by depressing that side thereof toward the inside of the turn and located generally in planes intersecting below the bottom of the boat.

6. A boat comprising, in combination, a single semisubmerged or surface propeller at the stern thereof, fixed means adjacent the propeller for counteracting the paddling action thereof and bow rubber means for steering the boat.

7. A boat comprising, in combination, a hull of the inverted V-bottom type and bow rudder means located generally in planes intersecting below the bottom of the boat.

8. A boat comprising, in combination, a hull of the inverted V-bottom type and twin bow rudders, each generally perpendicular to the general plane of the adjacent portion of the inverted V-bottom of said boat.

9. A boat comprising, in combination, bow steering means providing for banking of the boat when turning at speed, and means adjacent the stern of the boat contributing to banking of the hull when turning at speed.

In testimony whereof, I have signed my name to this specification.

WILLIAM ALBERT HICKMAN.

CERTIFICATE OF CORRECTION.

Patent No. 1,670,623.

Granted May 22, 1928, to

WILLIAM ALBERT HICKMAN.

It is hereby certified that error appears in the printed specification of the above numbered patent requiring correction as follows: Page 2, line 77, claim 3, for the misspelled word "ruders" read "rudders"; same page, line 101, claim 5, for the words "submerged surfaces" read "immersed portions" and line 102, for "immersed portions" read "submerged surfaces"; and that the said Letters Patent should be read with these corrections therein that the same may conform to the record of the case in the Patent Office.

Signed and sealed this 10th day of July, A. D. 1928.

(Seal)

M. J. Moore,
Acting Commissioner of Patents.
